UNITED STATES PATENT OFFICE.

EMIL KLAHN, OF NEW VERNON, NEW JERSEY.

ART OF SUSTAINING BODIES IN SPACE.

Application filed October 1, 1917, Serial No. 194,211. Renewed October 20, 1926.

The invention relates to floating bodies such as gyroscopes or spinning bodies, suitable for scientific and industrial purposes, and more particularly to the manner of sustaining and of effecting the rotation of a suitable mass so that the same shall have perfect freedom of rotation, that is to say, be possessed of the requisite three degrees of freedom of rotation and, also, substantially free in space,—being without material or other connection with the earth—the said mass constituting in effect a mathematical gyroscope. In carrying out the invention, I employ a suitable fluid, such as air, to effect the rotation of said mass as well as to afford the desired freedom thereof. A further object of the invention consists in maintaining the rotatable mass in predetermined relationship to another or secondary and floating portion of the apparatus.

In the accompanying drawings, which illustrate the invention—

Fig. 1 is an elevation of the improved gyroscope.

Fig. 2 is a plan of the same with the rotating mass removed.

Figs. 3 and 4 are vertical sections of the apparatus illustrating the relation of the parts respectively in inoperative and operative position.

Similar characters of reference designate corresponding parts thruout the several views.

Referring to the drawings, 10 designates a suitable base or support upon which rests, normally, a hollow, cylindrical body 11 or secondary floating member, the underface 12 of which is made substantially parallel to the upper surface 13 of the base 10, the two said surfaces being in contact (Fig. 3) when the gyroscope is not in operation. At its upper end, the cylinder 11 is concave to provide a depression, cavity or bowl 14, which is shown of spherical outline and is accurately finished to receive a rotatable mass or primary floating member 15 shown in the form of a sphere, the same being constructed as nearly perfect as possible so that there shall be no preponderance of weight in any direction. A tube 16 projects upwardly and centrally from the base of cylinder 11, and within same is a second tube 17 coaxial therewith and extending upwardly from the base 10, said latter tube communicating with an outside source of fluid supply (not

shown), as thru a suitable connection 18. The tube 17 thus affords a central passage-way for the supply of fluid to the interior of the cylinder 11, and the entire cylinder is designed to be freely rotatable about the innermost tube 17. For this purpose, it is preferred to provide the said innermost tube 17 with an annular enlargement 19 designed to coact with an agate or other bearing 20 set into the inner wall of tube 16. A slight play is left between the annulus 19 and bearing 20, which will allow for oscillation of the cylinder 11 about a horizontal axis perpendicular to the vertical axis of the tubes when the cylinder 11 is raised off the base 10, as will be hereinafter set forth.

A narrow duct or nozzle 25 extends thru the upper wall of bowl portion 14 of the cylinder, being in the nature of a slit cut preferably at an angle and displaced slightly from the pole of the bowl to direct a stream of fluid tangentially against the mass 15 in the direction of its spin. The fluid thus received from the interior of cylinder 12 and directed thru nozzle 25 between the surface of the spherical mass or ball 15 and the bowl 14 causes the former to rotate at an extremely high velocity, and at the same time to provide an unconfined air cushion which serves to lift the entire mass (Figs. 1 and 4) an appreciable distance out of the said bowl 14. The ball 15, therefore, is rotating with absolute freedom, having the requisite three degrees of rotation and is without support other than the said air cushion formed between it and the surface of bowl 14. In other words, the ball is, in effect, absolutely free in space and without material or other connection to the earth. Furthermore, when pressure is thus applied in the rotation of the ball 15, sufficient force will be exerted upon the cylinder 11 to raise the same off its base 10; and the said cylinder, thereupon, also becomes entirely free from any material or other connection to the earth, having an unconfined air cushion between its lower face 12 and the upper surface 13 of the base 10. It will be understood that its motion about an horizontal axis perpendicular to its vertical axis is, of course, limited by the play between annulus 19 and bearing 20; but the said cylinder is perfectly free to rotate about its said vertical axis.

In order to retain the said cylinder 11 and ball 15 in a predetermined relationship to each other, one or more peripheral grooves

30 are provided on the ball or mass 15, the one being located along the equator of said ball, and the others symmetrically arranged with respect thereto. In the present embodiment, three such grooves are illustrated; and by providing similar grooves 31 in the bowl 14, it has been found that, when the two sets of grooves are displaced from each other, as in rotating the cylinder 11 with respect to ball 15, the two members are very quickly restored to the position where the two sets of grooves 30 and 31 coincide. In the case of the bowl, the grooves 30 need not extend entirely to the nozzle and are located, for example, in meridians of said bowl.

I claim:

1. In a gyroscope: a rotatable support member having an upper bowl portion; and a free, spherical member adapted to rest and to rotate therein and solely air supported during rotation.
2. In a gyroscope: a support member having an upper bowl portion; and a free, spherical member adapted to rest and to rotate therein and solely air supported during rotation, said support member being rotatably mounted relatively thereto and having a nozzle to supply air tangentially to the spherical member.
3. In a gyroscope: a free, spherical member solely air supported during operation; and a member rotatable relatively thereto to supply air to the spherical member for retaining same in its unsupported, operative condition and to effect the rotation thereof, said rotatable member being provided with means to cause the spherical member, thru the action of the intervening layer of air, to preserve its position relatively thereto.
4. In a gyroscope: a base, a spinning mass solely supported during operation by air to have three degrees of freedom of rotation per se; and an intermediate rotatable supporting member for the mass.
5. A gyroscope, comprising an air supported spherical mass, per se free to rotate during operation about two mutually perpendicular horizontal axes and about a vertical axis perpendicular to the plane of said horizontal axes; and an air supported carrying member therefor.
6. A gyroscope, comprising an air supported spherical mass, per se free to rotate during operation about two mutually perpendicular horizontal axes and about a vertical axis perpendicular to the plane of said horizontal axes; and an air supported carrying member therefor free to rotate about a vertical axis.
7. A gyroscope, comprising: a spherical spinning mass, solely air supported during operation, and a nozzle member rotatable relatively thereto in a horizontal plane to supply air for effecting the spinning of said mass.

8. A gyroscope, comprising: a spherical spinning mass, solely air supported during operation, and a rotatable nozzle carrying member to supply air for effecting the spinning of said mass, the former being provided with means to cause, thru the action of the intervening layer of air, the spherical mass to preserve its position relatively thereto.

9. A gyroscope, comprising: a rotatable sphere solely air supported during operation; a freely movable nozzle member, and means to support same, said nozzle member including a bowl to normally retain said sphere and the latter being adapted, during operation, to be free therefrom and the nozzle member from its support, when air is projected thru the nozzle member to rotate said sphere.

10. A gyroscope, comprising: a rotatable sphere solely air supported during operation; a freely movable nozzle member, and means to support same, said nozzle member including a bowl to normally retain said sphere and the latter being adapted, during operation, to be free therefrom and the nozzle member from its support, when air is projected thru the nozzle member to rotate said sphere, said sphere and support being provided with means to preserve, thru the intervening layer of air, the relative position of one to the other.

11. A gyroscope, comprising: a rotatable sphere solely air supported during operation; a freely movable nozzle member, and means to support same, said nozzle member including a bowl to normally retain said sphere and the latter being adapted, during operation, to be free therefrom and the nozzle member from its support, when air is projected thru the nozzle member to rotate the said sphere, said sphere being provided with positioning grooves and the said bowl with a groove corresponding thereto.

12. A gyroscope, comprising: a rotatable sphere solely air supported during operation; a freely movable nozzle member, and means to support same, said nozzle member including a bowl to normally retain said sphere and the latter being adapted, during operation, to be free therefrom and the nozzle member from its support, when air is projected thru the nozzle member to rotate said sphere, said sphere being provided with an equatorial groove on its surface and the bowl on its surface with a portion of a groove to correspond therewith.

13. A gyroscope, comprising: a rotatable sphere solely air supported during operation; a freely movable nozzle member, and means to support same, said nozzle member including a bowl to normally retain said sphere and the latter being adapted, during operation, to be free therefrom and the nozzle member from its support, when air is projected thru the nozzle member to rotate

said sphere, said sphere being provided with an equatorial groove on its surface and the bowl on its surface with a portion of a groove to correspond therewith and in the 5 plane of rotation of said sphere.

14. A gyroscope comprising a rotatable sphere solely air supported during operation; a base provided with a central tubular portion affording a supply of fluid; a hollow 10 cylindrical member provided with a central tubular portion surrounding the said tubular portion of the base and rotatable about same as an axis, said cylinder providing at its upper end a bowl to receive the spherical 15 mass, and having a nozzle extending from its interior to the bowl portion.

15. A gyroscope comprising a rotatable sphere, air supported during operation, a base provided with a central tubular portion affording a supply of fluid; a hollow 20 cylindrical member provided with a central tubular portion surrounding the said tubular

portion of the base and rotatable about same as an axis; an annulus formed on the tubular portion of the base, and an annular 25 bearing member secured to the inner surface of the tubular portion of the cylindrical member to coact therewith, said cylinder providing at its upper end a bowl to receive the spherical mass, and having a nozzle 30 extending from its interior to the bowl portion.

16. A portable ball-controlled instrument which comprises a stand, a pipe for compressed air passing through said stand, a 35 vessel adapted to be supported freely by said air upon said pipe as a guide, and a spinning ball supported and driven by said air inside said floating vessel.

Signed at New York in the county of 40 New York and State of New York this 28th day of Sept. A. D. 1917.

EMIL KLAHN.
